[57] CLAIM

The ornamental design for tips for orthodontic band-seating plier, substantially as shown and described.

DESCRIPTION

FIG. 1 is a top perspective view of tips for an orthodontic band seating plier, showing my new design;

FIG. 2 is a side elevational view thereof;

FIG. 3 is a bottom plan view thereof;

FIG. 4 is an elevational view of the side opposite that shown in FIG. 2;

FIG. 5 is a top plan view thereof;

FIG. 6 is an end elevational view thereof.

The broken line disclosure shown in all views is for illustrative purposes only and forms no part of the claimed design. The plier tips are shown opened in FIG. 1 and closed in the remaining views.
